UNITED STATES PATENT OFFICE.

GEORGES KINSBOURG, OF REMIREMONT, FRANCE.

LAPPET-LOOM.

SPECIFICATION forming part of Letters Patent No. 637,129, dated November 14, 1899.

Application filed August 28, 1897. Serial No. 649,809. (No model.)

To all whom it may concern:

Be it known that I, GEORGES KINSBOURG, manufacturer, of Remiremont, Vosges Department, in the Republic of France, have invented new Improvements in Lappet-Looms for Weaving Figured Fabrics, (for which I have obtained Letters Patent of France for fifteen years, No. 267,058, dated May 18, 1897;) and I do hereby declare that the following is to a full and exact description thereof, reference being made to the accompanying drawings.

It is known that in the manufacture of broché goods the design is made by passing the thread which is to form the said design over certain threads of the weft and under all the others, the said broché thread extending from one point to another on the wrong side of the cloth. Heretofore this operation has been done either by hand or with devices allowing of making only one type of design on one and the same loom.

This invention relates to an improved apparatus called a "broché lathe" and which can be adapted to either a hand or power loom and which allows of varying at will the designs without having to change any of the parts of the said loom. One and the same design can also be reproduced on any scale and be enlarged or reduced as the operation is being proceeded with. In order to insure this double result, I adapt onto the ordinary lathe of the loom a second lathe or "lathe for broché goods," which has an upward and downward movement imparted to it during the operation. The upper horizontal piece of this lathe placed under the warp-threads of the cloth carries a series of vertical needles, through which pass the broché threads, the assemblage of which is parallel to that of the warp-threads and situated under the latter. When the broché lathe is in its uppermost position, the needles are engaged between the warp-threads, and the assemblage of the broché threads is also raised up, so that if at this moment the shuttle is put in motion the weft-thread will be passed under all the broché threads, which will thus be caught in the cloth. As soon as the broché lathe moves down its pins are disengaged from the warp-threads and the piece which carries them is then moved aside, whereby each needle jumps

over a certain number of warp-threads, the result being that when the upward movement again takes place the fresh broché stitch made by each needle is situated a certain distance to the right or left of the foregoing stitch. These lateral movements of the piece carrying the needles are obtained by means of a wheel the rim of which is provided with pins of varying lengths. At each stroke of the lathe one of the said pins comes and acts laterally on the end of a lever having a fixed fulcrum and jointed at its opposite end to the comb of the broché lathe. It will thus be understood that the longer or shorter the pin the lever will oscillate more or less and the comb will be displaced to a greater or less extent, whereby each broché thread may be caused to make a predetermined design by arranging beforehand the length of the different pins on the rim of the operating-wheel, the said design being, moreover, the same of all the broché threads. It will also be understood that by displacing the oscillating center of the lever which controls the movements of the comb of the broché lathe the same series of operating-pins may be made to produce the same designs on the cloth, but reduced or enlarged, the lever then operating as a pantograph. Hence in order to change the size of the broché design all that is needed is to change the oscillating center of the lever, and in order to change the form of the design the length of the pins is changed, an operation which is readily and easily done by screwing or unscrewing the said pins in the rim of the wheel which carries them, the pins thus moving inward or outward in a radial direction.

I have shown in the accompanying drawings the application to a loom of the broché lathe I have invented.

In the said drawings, Figure 1 is a back view in elevation of the said lathe. Fig. 1^a shows a detail. Fig. 2 is a sectional view on the line 1 2 of Fig. 1 as seen from the right, and Figs. 3 and 4 show one part of the operation of the lathe.

My broché lathe comprises a frame or support *a g k' p*, fitted onto the uprights *B* of the ordinary lathe in such a manner as to be able to slide vertically in the said uprights while being carried along by the latter when

moving. In the application shown in the drawings the ordinary lathe is pivoted at its lower part, so that the comb is at its upper part.

5 The upper cross-piece *a* of my broché lathe is arranged below and in front of the bottom *A* of the lathe of the loom and receives on its back face a piece *b*, which carries the needles *c* of the broché threads. The said needles, 10 placed in front of the bottom *A*, project beyond the upper face of the latter in the uppermost position of the broché lathe, as shown in Figs. 1, 2, and 3 of the drawings, and then descend below the level of the said 15 bottom, when the beating takes place, as also shown in Fig. 4. The piece *b* is provided with two horizontal slots *d d*, in which pass the stems of two screws *d' d'*, screwed in the cross-piece *a*, and in the projection on the back 20 face of the piece *b* is also a pin *e*, which enters the slotted or bifurcated end of a vertical oscillating lever *f*.

There only remains to be shown how I communicate the upward and downward movement to the broché lathe as a whole and the lateral variable movement to the piece *b* of the needles. To insure this twofold result, I fix onto a second horizontal cross-piece *g* of the broché lathe a simplified jacquard mechanism *j*, having only two needles or lifting-wires 1 and 2. To wire 1 are suspended two connecting-rods *h h'*, hooked at their opposite ends to one of the arms of the levers *l* and *l'*, having a fixed fulcrum *o*, and jointed at *i* and 35 *i'* of the uprights *k* and *k'* of the broché lathe. To the other wire 2 is hooked a small chain or rod *m*, attached at its opposite end to the controlling-lever *m'* of a pawl *n*. On the other hand, a yoke *p'*, fixed to the lower horizontal cross-piece *p* of the broché lathe and 40 to the frame of the mechanism *j*, carries a horizontal rotatory shaft *q*, on which are fixed a ratchet-wheel *r* behind and operated by the pawl *n* and then a second wheel *s*, carrying on its rim the pins *t*, radially arranged, and the projection of which can be increased or decreased by unscrewing or screwing the same, and in front a depression-wheel *u*, against the rim of which is constantly pressed, 45 by a spiral spring *u'*, a stop *u''*, the head of which is housed in the depressions of the wheel *u* and holds the shaft *q* fast after each partial rotation of the same. Lastly, the oscillating lever *f* revolves on a spindle *f'*, pivoted on the upright *k* of the broché lathe. The said lever *f*, the upper bifurcation of 50 which embraces the pin *e*, carried by the piece *b*, is provided at its lower part with the curved spratle or horn *f''*, constantly held pressed against the ends of the pins *t* by the tension of the spring *f''*, fixed at one end to the upper arm of the lever and at its opposite end to the upper cross-piece *a* and at a certain point of the latter. 55 The relative lengths of the arms of lever *f* can, if desired, be changed, for example, by removing nut *f'''*, Fig. 1^a, from the pivot *f'*

and transferring the pivot up or down to another hole *f'''* or by other suitable means.

Whether the loom is operated by power or 70 by pedals, a partial movement of rotation of about one-fourth of a revolution is transmitted either by suitable means or direct to the horizontal shaft *j'* of the jacquard mechanism for each beating stroke of the loom. 75 This movement causes the griffe or ram *c''* of the mechanism to rise. The cards which unwind from the roller *J* cause the needles 1 and 2 to be carried along by the ram, and consequently the raising of the rods *h*, *h'*, and *m*. 80 The fulcrum *o* of the levers *l* and *l'* being fixed to a suitably-supported standard *o'* and the smaller arms of the said levers being raised, the greater arms are lowered, carrying with them the whole of the broché lathe 85 in their downward movement. As soon as this latter movement begins the needles *c* of the broché threads become disengaged from the warp-threads, and the pawl *a* forcing at this moment the ratchet-wheel *r*, and consequently the shaft *q*, to turn one of the pins *t* of the wheel *s* pushes the lower arm of the lever *f*, and the said lever *f* oscillates and carries with it in its lateral movement the piece *b* and the needles *c*. As soon as the rotation of the shaft *j'* ceases the downward movement of the broché lathe stops, as well as the horizontal movement of the piece *b*. The spiral springs *V* and *V'*, which have become compressed between the cross-piece *g* of the broché lathe 90 and the lugs *x* on the uprights *B* of the ordinary lathe, open and bring the broché lathe back to its uppermost position and the ram of the mechanism to its lowermost position. The tension-spring *f''* causes the piece *b* of 95 the needles *c* also to move back and the lever *f* to press on the following pin *t* of the wheel *s*. 100

The perforations of the cards of the jacquard mechanism allow of raising simultaneously both of the wires 1 and 2, or simply wire 1. 110 When wire 2 is not raised, each broché thread makes successive stitches placed in the same line parallel to the warp-threads.

In any case all the broché threads make simultaneously the same design in the cloth. 115 In order to enlarge the said design, all that is needed is to lower the oscillating center *f'* of the lever *f*, which increases the length of the upper arm of the said lever and decreases the length of the lower arm of the same. Inversely, to reduce the broché design the center of oscillation *f'* of the lever *f* is raised. 120

Figs. 3 and 4 show the positions of the broché threads when the broché lathe is in its uppermost and lowermost positions. 125 When the said lathe is in the former position, the broché threads 3 are raised and are nearly in line with the upper assemblage 4 of the warp-threads. A stroke of the shuttle is then given, and the weft-thread 5 lies under the 130 warp-threads 4, under all the broché threads 3, and above the second assemblage 4' of the warp-threads, the broché lathe moves down again, the beating of the cloth takes place,

and the assemblage 3 of the broch<é> threads, as well as the assemblage 4 of the warp-threads, lie at the lower part, while the assemblage 4' of the warp-threads lie at the 5 upper part. If then a stroke of the shuttle is given, the weft-thread 5' comes up above all the broch<é> threads, the beating is done, the broch<é> lathe comes up again, and so on. When it is required to stop the operation of 10 the broch<é> threads, while continuing the weaving of the cloth, the broch<é> lathe is brought by hand to its lowermost position and then fixed there by any suitable means. The operating parts of the jacquard mechanism are 15 put out of movement at the same time.

Such is the simple apparatus, which can be applied to any system of loom and which allows of making the broch<é> goods of all sorts of designs, the form and size of which can be 20 readily varied, without having to change any of the parts of the said apparatus.

I reserve to myself the right of varying at will the forms, the materials, and the dimensions of the different organs of my lathe with 25 drop-box for broch<é> goods and of completing the same by any suitable operating or transmitting device according to the types of power or hand looms to which the said lathe may be applied.

30 I claim—

1. The combination with the lathe of a loom and the frame B thereof, of a broch<é> lathe comprising a vertically-movable frame, the broch<é> lathe being carried by and vertically movable

35 with the frame B, bar b, broch<é> needles c carried thereby; said bar b being fixed to the top of the broch<é> lathe but being movable to the right and left, and a jacquard mechanism having two hooks or wires 1, 2, levers l, l' pivoted to the broch<é> frame, a fixed pivot for said 40 levers, means for connecting said levers on the opposite side of their fixed pivot from the connection to the broch<é> frame of wire l, a pattern-wheel s with pins t, a propelling-pawl m, and a connection between said pawl and 45 wire 2, substantially as described.

2. In a loom a broch<é> lathe comprising in combination a framework a, g, k, k', p, capable of sliding vertically, beams B, B on which said framework slides, a piece b carrying the 50 needles of the stitching-threads, piece b being movable to the right or left on the part a of said framework, an oscillating lever f, a pivot f' adjustable as to height, a support k², a wheel s provided with radial pins t more or 55 less screwed into holes in the wheel s, a jacquard mechanism having two hooks or wires 1, 2, levers l, l' pivoted on the fixed axis o and jointed at i, i' on the pieces k, k' of the frame, devices h, h' connecting said levers to the 60 hook or wire 1, a pawl m controlled by the hook or wire 2, and a ratchet-wheel r.

In witness whereof I have hereunto set my hand in presence of two witnesses.

GEORGES KINSBOURG.
